W. WILLARD SOWLES, OF MANLIUS, NEW YORK, ASSIGNOR TO HIMSELF AND A. D. WILCOX, OF SAME PLACE.

Letters Patent No. 88,818, dated April 13, 1869; antedated January 18, 1869.

IMPROVEMENT IN GATES.

The Schedule referred to in these Letters Patent and making part of the same.

To all whom it may concern:

Be it known that I, W. WILLARD SOWLES, of Manlius, in the county of Onondaga, and State of New York, have invented a new and improved Method of Hanging Gates; and I do hereby declare that the following is a full, clear, and exact description thereof, which will enable those skilled in the art to make and use the same, reference being had to the accompanying drawings, forming part of this specification, in which—

Figure 1 shows the gate in a closed position, and Figure 2 shows the position when open.

Similar letters of reference indicate like parts.

This invention consists in a certain new and useful improvement in hanging gates, whereby a gate is self-closing, cannot be hoisted off its hinges by hogs or cattle, is easily removed, when desired, and in opening is elevated, so as not to be obstructed by snow, as hereinafter explained.

The lower part of the gate A is provided with a hinge, B, which is formed by a hook fixed in the post C, and an eye-bolt in the gate, which engages with said hook. The upper part of the gate is provided with a bolt, or upward projection e, which is secured to the gate in a fixed manner, and engages with a slotted plate, D, which is secured to the post C.

Between the connection e D and the hinge B is a hooked rod, or link F, which also makes connection between the gate and post by means of eye-bolts f a, the eye-bolt f being placed in the post C, not directly above the lower hinge B, but to one side, as shown in fig. 2.

When the gate is opened, the rod or link F checks the upper part of the gate over the bolt e, traversing the slotted plate D, and sustaining the head of the gate

in connection with said link F, so that its outer end is elevated, as seen in fig. 2, and this not only stores up force to cause the gate to close itself, but raises the bottom of the gate so as to clear obstructions of ice and snow, which are always a source of greater or less annoyance with close fitting gates, especially the larger class, or farm-gates.

The eye-bolt f is put in the post C, so as to be turned therein, and, when desired, the gate is quickly removed, by turning the bolt f half around and unhooking the link F therefrom, which allows the hinge B and the upper connection D e to be then disengaged. In this manner the gate is self-closing, and at the same time that it is removable cannot be hoisted by hogs or cattle, and thrown from its hinges.

The gate is designed as either door-yard or farm-gate.

A detent-notch, d, fig. 1, in the slotted plate, for receiving the bolt e, can be used for retaining the gate in a wide-open position, but where a self-acting detent is not preferred, hooks can be provided for holding the gate open.

Having thus described my invention,

What I claim as new, and desire to secure by Letters Patent, is—

The combination of the hinge B, link F f, and connection D e, with gate A, constructed and operating substantially as herein set forth.

The above specification of my invention signed by me, this 9th day of November, 1868.

W. WILLARD SOWLES.
